UNITED STATES PATENT OFFICE.

ALEXANDER THOMAS PORTER, OF ELIZABETH, NEW JERSEY.

PROCESS OF PRODUCING LIQUIDS OF MEDICINAL VALUE.

Application filed February 10, 1921, Serial No. 443,783. Renewed May 25, 1927.

This invention relates to processes of producing liquids having medicinal value and is herein illustrated as producing such liquids from hydrocarbon oils.

5 I have discovered that certain of the liquid hydro-carbons such as, for instance, kerosene and fuel oil, when subjected under certain conditions to the direct action of a flame, undergo a physical or molecular 10 change which make them more available for medical purposes.

I shall further explain my invention with reference to the accompanying drawings, illustrating apparatus for carrying my invention into effect; thereafter I shall point 15 out the invention in claims.

Figure 1 of the drawings shows an elevation, with parts in section, of an apparatus for carrying out the invention. Figures 2 20 and 3 are details of construction.

The apparatus consists of a special form of tank or receiver A for the combustible liquid, an air pump B for putting pressure on the tank A, a device C for subjecting the 25 combustible liquid to the direct action of a flame, for the purpose of changing its physical or molecular structure, a tank D for receiving any drip that may occur from the device C, a condenser E for bringing the 30 vapor product of device C back to liquid form and a tank F for receiving the liquefied vapor from condenser E.

The tank A consists of a cone-shaped container 1, preferably made of glass, supported 35 and firmly held by the frame 3 and head 2, bolted together by rods 4 as shown.

In carrying out the method claimed, combustible liquid, which may be ordinary kerosene oil, with or without medicine in solution 40 is poured into receiver 1 through opening 5, the opening then being sealed by gauge 6, a sufficient quantity of the liquid should be put in to submerge a considerable portion of tube 11, leaving however, sufficient 45 space for compressed air above the liquid.

Air for pressure on the tank is supplied by pump B through tube 8, the amount of pressure being indicated by gauge 6, and regulated by adjustment of relief valve 7.

50 By the introduction of the air to the bottom of container 1, as shown in the drawing, the combustible liquid in the tank is kept in a state of agitation during the operation of the process, thereby preventing precipitation 55 of any of the constituents of the combustible liquid. Flange 8^a on tube 8 protects the

open or intake end of the oil tube 11 from the ascending air forced in through tube 8.

When the required air pressure is obtained in the tank A a continuous flow of air 60 and oil, under pressure, to the atomizer 14, can be maintained by operating valves 12 and 13 in tubes 10 and 11. 12^a and 13^a are needle valves in the air and oil lines between tank A and atomizer 14, adjusted to determine the proportion of air and oil used in atomizing the combustible liquid.

The atomizer 14 is held in position in sleeve 19 by set-screw 20. When the air and oil, under pressure, meet at 15 in nozzle 16, 70 a continuous, finely divided atomized spray is projected into flame chamber 27, which can then be ignited by a spark plug or by a lighted match through opening 24; opening 24 can then be sealed by gate 25, movable on pivot-screw 26.

The flame in flame chamber 27 is maintained by combustion-supporting air, annularly admitted to the combustion chamber 27 through openings 18 and 23, and the 80 amount of air so admitted determines the intensity of the flame.

The disc 17 screwed into end of flame chamber 27, with its sleeve 19 carrying the atomizer 14, seals the upper end of the flame chamber except for the annular openings 23. The ring 21, movable and held in place by nut 22 screwed on to sleeve 19, has also annular perforations 18 coinciding with the openings 23. By a movement of ring 21, the 85 amount of coincidence between the openings 18 and 23 is determined, thereby controlling and regulating the supply of combustion-supporting air. Screens 21^b screwed into flange 21^a of ring 21 prevents any back flare 90 through openings 18 from reaching the vapor outside the apparatus. Tube 32 carrying the drip from device C to tank D is secured to tube 29 at 31. A vent 33 is provided in tank D.

The vapor produced by the action of the flame, being restricted in its flow through passage 28, extinguishes the flame at that point and passes on through tube 29, which is attached to extension 30 of restriction 28, 105 and is delivered to coil 34 of condenser E which extends outside jacket 44 and 35^a, as shown.

The vapor produced by the flame action is drawn down through condenser coil 34 and 110 forced up through reverse condenser coil 35 by blower G, any uncondensed vapor pass-

ing through coil 35 passes through extension tube 36 and again enters coil 34 at 37. Tank F has a vent tube 42 connected with coil 34, as shown, which produces a slight vacuum in the tank, causing the liquefied vapor from condenser E to flow into the tank through tubes 39 and 41. The liquefied vapor can be recovered from tank F through valve 43.

To those skilled in the art to which this invention belongs, it will be apparent that there is an important relation between the diameter and length of the combustion chamber and the amount of the material passing through it.

15 The diameter of the flame chamber determines the velocity of the material passing through; consequently, the diameter and length of the flame chamber determine the time action of the flame.

20 An important feature of the vaporizing portion of the method is to bring the atomized stream to the required degree of fineness with the least amount of atomizing air. The atomizer shown is designed to give effect to 25 this feature by bringing the air and oil first in contact at 15 close to the opening in the atomizing nozzle 16.

The degree of fineness of the atomized spray, the amount of combustion-supporting 30 air admitted and the degree to which the combustion air penetrates the atomized spray determine the amount of combustion taking place in the combustion chamber. As the atomizing nozzle is advanced into the 35 flame chamber the more deeply will the combustion air penetrate the atomized spray.

The condensed liquid is suitable for ad-

ministering free or in capsules or in such other form as a doctor may desire, and has proved especially useful in the treatment of 40 tuberculosis, asthma, bronchitis, pneumonia and other catarrhal diseases.

I claim:

1. The process of producing a liquid for medical purposes, which consists in supplying a hydrocarbon liquid with an admixture of air insufficient for the complete combustion of the same, subjecting the mixture to a partial combustion whereby the remainder is vaporized, and condensing the mixed vapors to produce a liquid suitable for internal and external administration. 45

2. The process of producing a liquid of low irritability and high absorbability for medical purposes which consists in supplying a hydrocarbon liquid with an admixture of air insufficient for the complete combustion of the same, and burning part of it in a finely divided stream to vaporize the remainder, and condensing the vapor to produce a liquid product having such characteristics. 50

3. The process of producing a liquid of low irritability and high absorbability for medical purposes which consists in supplying kerosene with an admixture of air insufficient for the complete combustion of the same, and burning part of it in a finely divided stream to vaporize the remainder, and condensing the vapor to produce a liquid 55 product having such characteristics. 60

In testimony whereof, I have affixed my signature to this specification.

ALEXANDER THOMAS PORTER.
